UNITED STATES PATENT OFFICE.

ALFRED MORELL, OF MILLBURY, MASSACHUSETTS, ASSIGNOR OF ONE-HALF
TO JOHN B. BRADY, OF SAME PLACE.

LOOM.

SPECIFICATION forming part of Letters Patent No. 655,262, dated August 7, 1900.

Application filed February 19, 1900. Serial No. 5,732. (No model.)

To all whom it may concern:

Be it known that I, ALFRED MORELL, of Millbury, in the county of Worcester and State of Massachusetts, have invented certain new and useful Improvements in Looms; and I do hereby declare that the following is a full, clear, and exact description thereof, reference being had to the accompanying drawings, forming a part of this specification, and in which—

Figure 1 represents a side view of so much of the harness mechanism of a loom as is necessary to illustrate the application of my invention thereto; and Fig. 2 is a similar view of said harness mechanism, showing the various parts in different positions from those shown in Fig. 1 to more fully illustrate the operation thereof.

The objects of my invention are to simplify the construction of the mechanism interposed between the "dobby-eveners" and the "jacks" or harness-levers and pattern-cylinder of a power-loom, so as to necessitate the use of only one "dobby-hook" instead of two, as ordinarily, also to economize in space, and to insure a positive action of said jack-actuating mechanism without the use of any springs whatever.

Said invention consists in combining with each jack or harness-lever, with each reciprocating dobby-evener, and the pattern chain-cylinder an eccentric adapted to engage with said jack or harness-lever; a vertical swinging supporting-arm; a horizontal link connecting the bottom of said swinging arm with said eccentric; a long horizontal lever pivoted at one end to said swinging arm, its other end extending out between the reciprocating dobby-eveners and provided with shoulders or hooks, one upon the top and the other upon the bottom edge thereof, against which said dobby-eveners are adapted to engage in their horizontal reciprocating movements; a small rocking lever or dog arranged about central under each dobby-hook and adapted to engage therewith, and a long hooked rocking lever adapted to engage at one end with said small rocking lever or dog and at its other end with the dobby-hook; and with the under edge of which long rocking lever the usual pins on the pattern-cylinders

are adapted to engage, as and for the purpose hereinafter more fully set forth.

To enable others skilled in the art to which my invention appertains to better understand the nature and purpose thereof, I will now proceed to describe it more in detail.

In the drawings, A represents part of one of the jacks or harness-levers, which is fitted to rock on the usual transverse shaft B and whose rocking movements are limited by the stationary cross-bar C, against which the shoulders A' A² on the jack come in contact when said jack is reciprocated back and forth in the operation of weaving, as usual.

D represents the pattern-cylinder, which is mounted on the transverse shaft E and provided with the usual radially-projecting pins D', the number of which, as will be understood, being governed by the pattern of the goods to be woven. In this instance only one of said pins is shown.

The intermittently-reciprocating slides or what are commonly termed "dobby-eveners" F F' are operated back and forth horizontally, as usual, by suitable mechanism connecting the same with the driving mechanism of the loom. As said mechanism and also that for operating the pattern-cylinder D do not constitute a part of my invention it is deemed unnecessary to illustrate or describe the same in detail. In Fig. 1 of the drawings I have shown by dotted lines the dobby-eveners F F', each separately connected by suitable adjustable bars or rods G with the ends of a rock-lever H, centrally pivoted to a transverse shaft I, one dobby-evener being connected with one end of said rock-lever and the other with the other end thereof. The rock-lever is provided with a central arm H', projecting at right angles therefrom, to the outer end of which is pivoted a vertically-reciprocating connecting-rod J.

The foregoing-described parts, it will be understood, are all old, and I make no claim thereto, except in combination with my improvements, which I will now describe. In describing said improvements it will also be understood that the mechanism for operating each jack is alike, and therefore only one set of jack-operating mechanism will be described, and as shown in the drawings.

Upon a stationary transverse shaft K is mounted and fitted to turn an eccentric L, said eccentric being located at the junction of the upright arm A³ and horizontally-projecting arm A⁴ of jack A and adapted to engage with the edges of said arms when said eccentric is turned, as hereinafter described. The eccentric is pivoted near its top edge to the transverse shaft K, and at the side edge farthest from arm A³ is pivoted one end of a horizontally-arranged link M, whose opposite end is pivoted to a vertical swinging arm N, in turn pivoted at its upper end to a stationary transverse shaft O. To the bottom end of said vertical swinging arm N is also pivoted one end of a long horizontal lever P or what is termed the "dobby-hook." This extends out between the two doby-eveners and is provided with two shoulders or projections P' P², one upon the top edge and the other upon the bottom edge thereof, against which the doby-eveners F F' are respectively adapted to engage in their horizontal intermittent reciprocating movements when said doby-hook P is raised or allowed to drop down into the path of said doby-eveners, as hereinafter described.

The operation of elevating the doby-hook P, so that the doby-evener F may engage with the shoulder P', is performed by the pin D' on the pattern-cylinder D engaging with the bottom edge of the horizontal rock-lever Q outside of its pivot Q' and through the operation of said rock-lever operating the dog R, which engages with the under side of the doby-hook and lifts its hook P' into the path of the doby-evener, as aforesaid. When the above lifting pressure is removed, the doby-hook P drops down by its own weight or force of gravity out of engagement with the doby-evener F and into the path of the other doby-evener F'. The inner end Q² of the rock-lever Q is made hook-shaped, being curved upward and inward toward its pivot Q', and said hooked end fits in a recess formed in the dog R at the inner side of its pivot R'. It is therefore obvious that when the outer end of the rock-lever Q is elevated, as is shown in Fig. 1, the outer end R² of dog R will also be elevated, and thereby causes the doby-hook to be lifted into the position shown in said Fig. 1. The outer end Q² of the rock-lever is curved upward and inward similar to its other end Q³ and is adapted to engage with the under edge of the doby-hook when the lever is forced upward, as is also shown in Fig. 1. In order to impart to said lever Q the desired rocking motion to keep its end Q³ and the dog R in proper engagement with the under side of the doby-hook to hold said doby-hook in its proper positions as it is reciprocated back and forth, the bottom edge of said rock-lever is made curving or cam-shaped at Q⁴, so that when the pin D' passes by in its rotation in contact therewith said movements will be imparted thereto.

Having described the various parts of my improvement in detail, I will now give a brief description of the operation thereof in practice.

Assuming that the jack or harness-lever A occupies the position shown in Fig. 1, with its upper vertical arm swung to the right, which is the position it occupies when the harness connected therewith is raised and also assuming that all the various parts to which my improvements relate are in their proper positions for holding the doby-hook in its elevated position, with the doby-evener F moved to its extreme right or outward position and the pin D' bearing nearly vertically against the under side of the rock-lever Q, now as the pattern-cylinder D continues to turn toward the right the mechanism which operates the doby-eveners operates also to move the evener F toward the left and the evener F' toward the right, thereby moving the doby-hook longitudinally toward the left also and through the various connections described swinging the eccentric around from the position shown in Fig. 1 to that shown in Fig. 2, which causes the jack to be swung over also—its upper arm A³ toward the left and its lower arm A⁵ toward the right and upward—thus lowering the harness connected therewith.

In practice the parts are designed to be so constructed and arranged in relation to each other that as the doby-hook P is moved toward the left, as above described, the rock-lever Q and dog R will be allowed to drop down, thereby also permitting said doby-hook to descend, so that its hook P² will come in the path of the doby-evener F' in the return movement of the latter toward the right. Being now in position for said return movement the doby-eveners, which have been automatically stopped for a moment at the ends of their longitudinal movements, are automatically operated, thereby drawing all the parts toward the right and causing the eccentric to bear down upon the arm A⁴ of the jack, swings it back into its former position to raise the harness, and so on indefinitely by intermittent automatic operations as the doby-eveners are reciprocated back and forth.

The rotation of the pattern-cylinder D is so timed with the movements of the doby-eveners F F' that the doby-hook P will always be in position for said doby-eveners to engage therewith in said reciprocating intermittent automatic movements.

Having described my invention, what I claim therein as new, and desire to secure by Letters Patent, is—

1. In a power-loom, the jack or harness-lever A, having the arm A⁴; doby-eveners F, F' having horizontal, intermittent, reciprocating movements imparted thereto, and the pattern-cylinder D, provided with transverse pins or projections D', in combination with the eccentric L located at the junction of the arms A³ and A⁴ of jack A, and pivoted to transverse shaft K; link M pivoted at one

end to said eccentric and at its other end to the lower end of a swinging arm N; said swinging arm, pivoted to shaft O; the dobby-hook P, pivoted at its inner end to the lower end of said swinging arm and whose outer end extends between the dobby-eveners, and with which said dobby-eveners are adapted to engage in their reciprocating movements; the rock-lever Q, arranged under the outer end of the dobby-hook, adapted to engage therewith, pivoted to the transverse shaft Q' and with which the pin or projection on the pattern-cylinder is adapted to engage, and the dog R, pivoted to shaft R' and with which the inner end of said rock-lever Q engages, said dog also being adapted to engage with the dobby-hook, substantially as and for the purpose set forth.

2. In a power-loom, the intermittently-re-

ciprocating dobby-hook P, having a projection adapted to engage with the dobby-evener F and with another projection adapted to engage with the dobby-evener F', and said dobby-eveners, each adapted to have reciprocating movements imparted thereto, in combination with rock-lever Q, pivoted to shaft Q' and provided with the hooked ends Q² Q³, the end Q² being adapted to engage with the dog R, and the end Q³ with the dobby-hook P; said dog R pivoted to shaft R' and also adapted to engage with said dobby-hook P, and with the pattern-cylinder D and its pin D', substantially as and for the purpose set forth.

ALFRED MORELL.
